INVENTOR -
Edwin W. Smith

UNITED STATES PATENT OFFICE.

EDWIN W. SMITH, OF BEVERLY, MASSACHUSETTS, ASSIGNOR TO UNITED SHOE MACHINERY CORPORATION, OF PATERSON, NEW JERSEY, A CORPORATION OF NEW JERSEY.

MARKING-MACHINE.

1,360,460.

Specification of Letters Patent. Patented Nov. 30, 1920.

Application filed October 12, 1918. Serial No. 257,910.

To all whom it may concern:

Be it known that I, EDWIN W. SMITH, a citizen of the United States, residing at Beverly, in the county of Essex and State of Massachusetts, have invented certain Improvements in Marking-Machines, of which the following description, in connection with the accompanying drawings, is a specification, like reference characters on the drawings indicating like parts in the several figures.

The present invention relates to machines for marking various objects, as portions of shoe uppers, and has to do more particularly with apparatus in which marking members may be set in various positions to produce different characters.

In such machines the usual expedient is to employ a single setting instrumentality which is successively brought into coöperation with all the marking members which are to be set. This time-consuming process is avoided by my invention, which provides means simultaneously movable into coöperation with different marking members for the independent setting thereof. By this arrangement, plural members may be simultaneously brought to the desired position with considerable economy of time. As illustrated, the setting means, while capable of actuation independently in the setting movement, are movable together in the selection of the marking members. Preferably I arrange members constituting the setting means oppositely, there being groups of these opposite members, appearing as alined concentric sleeves, each sleeve having a projection arranged to enter recesses in the series of marking disks to be set. The connection between the opposite setting sleeves, which causes their travel together, is shown as consisting of a rod passing through them, and also as a rod movable in a support and being joined to the sleeves. I prefer to so arrange the setting members that they normally operate on the more frequently set marking members. There is illustrated herein a series of marking members having less frequently set members interposed between those more frequently set, with these and the setting means spaced to permit the latter to be in normally operative relation to the more frequently used marking members. Then, when necessary, by moving the setting members through a space

equal to the width of the interposed marking members only, the entire setting means may be brought into coöperation with the less frequently set members. To guide the operator in setting the marking members, I have shown indicating means for determining the position of each of the setting members.

A single one of the several forms which my invention may assume is illustrated in the accompanying drawing. Here,

Figure 1 is a side elevation of a marking machine having my invention applied thereto;

Fig. 2 is a partial front elevation looking from the left in Fig. 1, with portions in vertical section;

Fig. 3 is a vertical section on the line 3—3 of Fig. 2; and

Fig. 4 is a detail in front elevation of the index member for the setting means.

In a frame 10 is supported for oscillation toward and from a work-support 12, a marking head 14, preferably under the influence of suitable mechanism driven by power applied to a pulley 16. At the forward extremity of the head between separated supporting walls 18, 18 is mounted a series of marking members 20. These marking members are shown in the form of disks 22 rotatable about a tubular spindle 24 fixed at the lower portion of the forward end of the head between the walls 18, 18, each disk having projections or teeth 26, the ends of which carry dies consisting of characters 28 which are to be impressed upon the work. Referring to Fig. 2, which shows a machine arranged for stamping parts of shoe uppers, we have on the first two disks at the right tens and unit size designations, followed by the half-size mark disk, then two disks bearing width symbols, after which are two disks for match marks, and finally six disks with series of digits for the case numbers. At least one tooth on each disk, as indicated at 28 in Fig. 3, is shorter than the associated teeth to permit the disk to be set to make no impression. Heat may be supplied to the disks by some such device as an electrical unit 30 situated within the spindle 22.

Above the marking disks appear setting disks 32, one for each of the disks 20, arranged between the walls 18, 18 and having alined central openings through which pass the setting means for manipulation by the

operator. This setting means is movable longitudinally in the series of disks 32 to actuate any one of them, and in the present embodiment of the invention it is adapted 5 for setting four of said disks without this movement of translation. For this purpose, the setting means consists of members arranged in opposite groups of two each. For these members I prefer to employ tubular 10 shafts or sleeves, there being two concentric sleeves in each group, an inner 34 and an outer 36. The outer sleeves are journaled in the walls 18, and through the inner passes a rod or shaft 38 holding the groups together. A spacing washer 40 surrounds the 15 rod 38 between the ends of the sleeves 34, its width being preferably equal to that of two of the setting disks. At the inner extremity of each of the sleeves 34 is a flange 20 42 which is equal in diameter to the outside of the sleeves 36. Upon the sleeves 36, the flanges 42 and the washer 40, the disks 32 are arranged to turn. They are normally held in the angular position to which they 25 are set, by spring fingers 44 fixed upon a bar 46 bridging the space between the walls 18, said fingers having enlarged end portions 48 for entering the spaces between the teeth. Upon the inner end of each sleeve 30 36 and upon each of the flanges 42 is a peripheral projection 50. These projections are movable by the longitudinal travel of the setting sleeves through a series of recesses 52 connected with the central openings 35 of the disks 32, these corresponding in number and position to teeth 54 projecting from the disks 32 similarly to the teeth 24 of the disks 20 and meshing therewith. The length of the sleeves 34 and 36 is such as to permit 40 the movement of the projections 50 into any of the recesses 52, and fixed upon their outer ends are hand wheels 56, one for each sleeve, the diameter of the inner pair of wheels being preferably greater than the outer pair 45 to permit the operator to manipulate conveniently the separate setting sleeves. The hand wheels are held against shoulders upon the sleeves by screws 58 threaded into the ends of the rod 38 and bearing against the 50 outer pair of wheels. When the sleeves are rotated, the projections 50, by their engagement with the recesses 52 which they occupy, turn the corresponding disks 32, and through the intermeshing teeth 24 and 54 set the marking disks 20.

In addition to the rod 38, the opposite groups of setting sleeves are connected by a rod 60 passing through aligned openings in upward extensions 62 of the marking head. 60 This rod is joined to the sleeves 36 by arms 64 surrounding said sleeves and bearing against shoulders upon them, the opposite or upper ends of the arms being secured to the rod by nuts 66. Fixed to the rod 60 is 65 a member 68 having an indicating point 70

for each of the sleeve projections 50 and in vertical alinement therewith. The ends of the teeth 54 preferably bear index characters 72 corresponding to the dies upon the teeth 24. The parts are so related that when 70 a character 72 is beneath the corresponding index point 70, the like die upon a tooth 24 will be in marking position.

I prefer to have the setting projections of the sleeves normally within the recesses of 75 the disks bearing the unit size designations, the half-size symbols, and those for the match marks. These characters in marking shoe uppers are more or less frequently changed during the stamping of the shoes 80 which are to make up a case. The width number, however, customarily remains the same for the entire case, and the case number, of course, does not change until the work for a new case is to be stamped. With 85 the setting means in this position, the operator can, by manipulating a hand wheel at either side of the head, simultaneously turn the corresponding disks, by the engagement of the sleeve projections with the recesses 90 52, to bring any desired character thereon into marking position, and can readily shift the grasp to the other pair of wheels to set the disks which these control. If the tens digit also is to enter into the size mark, the 95 movement of the setting means as a whole, by sliding the sleeves and connecting members together to the right in the head through the width of a single marking disk, renders this possible. When the case is 100 finished, bodily movement of the setting means to the left through the width of two marking disks from the normal position alines the setting projections with the disks bearing the width designations and the first 105 two disks of case numerals, so that the operator may adjust the disks for the width of shoes of this case and set its two highest numerals. Successive movements to the left permit the setting of the remaining case numerals, whereupon the setting means may be restored to its normal position.

Having thus described my invention, what I claim as new and desire to secure by Letters Patent of the United States is:

1. In a marking machine, a plurality of marking members arranged to be set in different marking positions, and connected means movable into coöperation with different members for simultaneously and independently setting a plurality of said members.
2. In a marking machine, a plurality of marking members arranged to be set in different marking positions, and independent 125 means movable together in the same direction into coöperation with different members for separately setting a plurality of said members.
3. In a marking machine, a plurality of 130

- marking members arranged to be set in different marking positions, and independent means movable as a unit into coöperation with different members for separately setting a plurality of said members, the setting means being arranged for normally operating upon more frequently set members. 5
4. In a marking machine, a series of marking members movable into different marking positions, there being less frequently set members between those more frequently set, and setting means spaced to coöperate simultaneously with the more frequently set members, said setting means being movable into coöperation with other marking members. 10
5. In a marking machine, a series of marking members arranged to be set in different marking positions, means movable together in the same direction into coöperation with different members for independently setting a plurality of said members, and means for determining the position of each setting means. 15
6. In a marking machine, a plurality of movable marking members, a plurality of setting means therefor, and means for connecting the setting means to move together. 20
7. In a marking machine, a plurality of movable marking members, a plurality of setting means therefor, and means for connecting the setting means to move together in one direction while being independently movable in another direction. 25
8. In a marking machine, a plurality of movable marking members, a plurality of setting means therefor, and means for connecting the setting means to move together into coöperation with different marking members, said setting means being independently movable to set the members. 30
9. In a marking machine, a plurality of disks provided with openings, and a plurality of setting members projecting into the openings and being movable into coöperation with different disks. 35
10. In a marking machine, a plurality of disks provided with aligned openings, and a plurality of setting members projecting oppositely into the openings and being movable together into coöperation with different disks. 40
11. In a marking machine, a plurality of disks, and concentric setting members movable into simultaneous coöperation with different disks. 45
12. In a marking machine, a plurality of disks provided with aligned openings, and a plurality of concentric setting members projecting oppositely into the openings and being movable together for simultaneous coöperation with different disks. 50
13. In a marking machine, a plurality of disks provided with openings, a plurality of setting members projecting into the openings and being movable into coöperation with different disks, and connections between said members to cause them to move together. 55
14. In a marking machine, a plurality of disks provided with aligned openings, a plurality of concentric setting members projecting oppositely into the openings, and connections between said members to cause them to move together. 60
15. In a marking machine, a plurality of disks provided with aligned openings, a plurality of concentric setting members projecting oppositely into the openings, and a connection within and extending between the opposite members. 65
16. In a marking machine, a support, concentric sleeves journaled therein and being movable axially, said sleeves having projections, and disks surrounding the sleeves and having recesses to receive the sleeve projections. 70
17. In a marking machine, a support, opposite, concentric, slidable sleeves journaled therein, a rod connecting the opposite sleeves, and disks surrounding the sleeves and arranged for actuation thereby. 75
18. In a marking machine, a support, opposite slidable sleeves journaled therein, a rod passing through and connecting the opposite sleeves, and disks surrounding the sleeves and arranged for actuation thereby. 80
19. In a marking machine, a support, opposite concentric sleeves journaled therein, a rod mounted to slide in the support, connections between the rod and sleeves, and disks surrounding the sleeves and arranged for actuation thereby. 85
20. In a marking machine, a series of disks, a plurality of setting members therefor, connections between the setting members, and an index member carried by the connections and coöperating with the disks. 90
21. In a marking machine, a series of disks, a plurality of setting members therefor, connections between the setting members, and an index member for each setting member carried by the connections. 95
22. In a marking machine, a support, opposite concentric sleeves journaled therein, a rod mounted to slide in the support, connections between the rod and sleeves, disks surrounding the sleeves and arranged for actuation thereby, and an index member mounted upon the rod and coöperating with the disks. 100

In testimony whereof I have signed my name to this specification.

EDWIN W. SMITH.
